UNITED STATES PATENT OFFICE.

HENRY M. GOODMAN, OF LOUISVILLE, KENTUCKY, ASSIGNOR OF ONE-THIRD
TO F. A. BAKER AND J. S. BELL, OF SAME PLACE.

CAR-AXLE LUBRICATOR.

SPECIFICATION forming part of Letters Patent No. 433,404, dated July 29, 1890.

Application filed May 15, 1890. Serial No. 351,859. (No model.)

To all whom it may concern:

Be it known that I, HENRY M. GOODMAN, a citizen of the United States, and a resident of Louisville, in the county of Jefferson and State 5 of Kentucky, have invented certain new and useful Improvements in Car-Axle Lubricators; and I do declare the following to be a full, clear, and exact description of the invention, such as will enable others skilled in the 10 art to which it appertains to make and use the same, reference being had to the accompanying drawings, and to letters of reference marked thereon, which form a part of this specification.

15 Figure 1 of the drawings is a representation of this invention, and is a vertical section with end views of the brasses. Fig. 2 is a perspective view of the brasses. Fig. 3 is a detail.

20 This invention relates to certain improvements in car-axle lubricators, being equally adapted for street-car, locomotive, and steam-car axles; and it consists in the construction and combination as will hereinafter appear.

25 In the drawings, A refers to the box, and B B' designate the brasses arranged in said box, one below and one above the axle C, each having a concave bottom surface, the upper one having in addition a central cavity

30 a, communicating with a lubricant or oil passage a', extending through the top of said brass. The upper brass B' rests and is held down upon the axle C by a wedge b, inserted between said brass and the top of the box A, and by means of the unoccupied space provided when said wedge is removed said brass can be readily removed when desired. The oil or lubricant cannot therefore escape when the axle is not in motion; but when the axle

40 is in motion the oil will be readily taken up thereby. The lower brass has at its sides supporting ledges or flanges b', which rest so as to have a little play in longitudinal grooves in the inner sides of the box A to provide for 45 oscillations of the axle. To the outer end of this brass is yieldingly held an end plate d by means of set-screws c, passing through vertical slots c' in said end plate and engaging screw-threaded apertures in said end of said

50 brass to accommodate the vertical oscillations or movements of the axle, while in order to

hold said brass up in contact at all times with the axle said end plate has a pendent stem or rod d, preferably encircled by a spring d', pressing upward against said end plate. 55

The drip or waste oil will be taken up by the lower brass and be thus fed to the axle and any surplus be passed off through the waste-pipe d'.

The lower end of the stem or rod d' passes 60 through the aperture in the horizontal arm of the bracket D to hold the spring in place, while the bracket itself, together with said end piece d, is permitted also to yield or rock laterally to respond to a like motion of the 65 axle, said bracket having a cylindric arm or pivot d', bearing or supported in an aperture in an arm or support e, secured to the end of the box A. This arrangement permits the end plate d to accommodate itself to any 70 movement or oscillation of the axle or box and yet retain its same position with relation to said axle. The end plate d heads up one end (the outer one) of the lower brass, thus converting the latter into a lubricant-reser- 75

voir. The lubricant or oil is fed from a common lubricant-reservoir (not shown) located at any suitable point on the car for the replenishing thereof through the pipe leading to a series of branch pipes f, one connecting 80 to each of a series of supplemental lubricant-reservoirs g. Each supplemental reservoir g is supported from or upon the truck of the car or engine and has a loose or sliding joint connection with a vertical pipe h, screwed or 85 secured at its lower end to the box A. The upper sliding end connection of the pipe h is rendered oil-tight by the packing i, fitting around the same and within the lower part of a supplemental oil-reservoir g and held in 90 place by the screw-cap j, screwed into the lower end of said reservoir and against said packing, said pipe passing through said cap. This arrangement provides for the independent vertical movement of said supplemental 95 reservoirs with the like movement of the cars, said reservoirs sliding upon the lubricant-pipes.

Having described this invention, what I claim, and desire to secure by Letters Patent, is—

1. In a car-axle lubricator, the combination,

with the axle-box containing an upper brass having an oil-receiving chamber, of the central-supply oil-reservoir and a supplemental reservoir secured on said box, a pipe connecting said reservoirs together, and a pipe having a sliding connection with said supplemental reservoir and secured to the axle-box, substantially as set forth.

2. In a car-axle lubricator, the combination, 10 with the lower brass, of the yielding end plate or piece having a pendent stem or rod engaging an aperture in a bracket pivotally supported in position, said stem or rod having a spring applied thereto, substantially as set 15 forth.

3. In a car-axle lubricator, the combination,

with the axle-box, of the lower brass having ledges or flanges loosely engaging grooves or ways in the inner sides of said box, the end piece or plate yieldingly connected to said brass at one end, and the bracket pivotally supported in position and having an aperture through which passes a stem or rod of said end piece surrounded by a spring bearing against said end plate and bracket, substantially as specified. 20 25

In testimony whereof I affix my signature in presence of two witnesses.

HENRY M. GOODMAN.
